Primary Examiner — Rhea Shields

(57) **CLAIM**

The ornamental design for an electrical box wall plate, as shown and described.

DESCRIPTION

This application claims the benefit of application Ser. No. 17/861,779 now utility patent U.S. Pat. No. 11,476,651 B1-Finish Material Interface Flange-George Emmanuel Mon as sole inventor and design patent application Ser. No. 29/923,036-Electrical Box Interface Flange-George Emmanuel Mon as sole inventor.

FIG. 1 is a front perspective view of a first embodiment of the electrical box wall plate;

FIG. 2 is a back perspective view thereof;

FIG. 3 is a front side perspective view thereof;

FIG. 4 is a back side perspective view thereof;

FIG. 5 is a back perspective sectional view taken along line 5-5 of FIG. 2;

FIG. 6 is a back perspective sectional view taken along line 6-6 of FIG. 4;

FIG. 7 is a side view, shown in an environment;

FIG. 8 is a front view, shown in an environment;

FIG. 9 is a back view, shown in an environment;

FIG. 10 is another side view, shown in an environment;

FIG. 11 is a front perspective view of a second embodiment of the electrical box wall plate; and,

FIG. 12 is a back perspective view thereof.

In FIGS. 7, 8, 9 and 10, the broken lines are for the purpose of illustrating environment only that form no part of the claimed design.

1 Claim, 12 Drawing Sheets
